UNITED STATES PATENT OFFICE

2,449,498

CHILD'S TOILET SEAT

Lawton B. Mellichampe, Washington, D. C.

Application April 5, 1946, Serial No. 659,923

5 Claims. (Cl. 155—131)

1
This invention relates to a toilet seat for children which may be connected to the conventional seat.

An object of the invention is to provide a toilet seat and cover which may be readily substituted for the conventional cover now in use.

Another object of the invention is to provide a child's toilet seat which may be readily attached to or removed from the conventional seat.

A further object of the invention is to provide a child's toilet seat which is readily constructed of non-critical material, and which may be readily manufactured in substantial quantities.

An additional object of the invention is to provide a seat of the type described having a top, arm supports and guard or safety bar which when in folded position provide a cover of attractive appearance.

An additional object of the invention is to provide a seat of the type described which may be constructed of a minimum number of parts.

Other objects will appear hereinafter from the specification.

In the drawings:

Figure 1 is a perspective view of the seat in open position.

Figure 2 is a top plan view of the seat in closed position.

Figure 3 is a side elevation of the seat in closed position.

Figure 4 is a vertical section taken centrally through the seat, and

Figure 5 is a fragmentary horizontal section of a detail of the invention.

The seat has a base 1. This seat is provided with the usual aperture 27. There is a back 2 which is mounted by hinges 26 to said base 1 as shown in Figure 2. The back has attached to it the armrests 3 and 4 by pivots 25. The forward ends of the armrests are supported by upright members 5 and 6. These members are pivotally connected at 25 to the armrests and their lower portions are pivotally connected to raised portions 7 and 8 of base 1, by hinges 24.

The base 1 may be readily attached to or detached from a conventional toilet seat by means of the hooks 18 shown in detail in Figure 5 having a curved portion 20 which extends into an aperture 19 of the seat. The hook is provided with an elongated shank 21 having a head 22. This shank and head are located within the recess 20, and the hook is normally urged to a closed position by the expansible spring 23.

When the seat is to be applied to the conventional toilet seat the cover for such seat is ordi-

narily removed or pivoted to its vertical position, whereupon the attachment of the present invention is applied by placing the same over the seat and pulling out the several hooks 18 which are snapped over the edges of the conventional seat.

The guard or safety bar 10 may be pivotally or rigidly attached to the arm 3 (by attaching means not shown). The opposite end of the safety bar may be hooked over the pin 11, as indicated in Figure 1.

It will be noted by reference to Figures 2 and 4 that the cover 2 may be held in its open or closed position by means of the following construction:

The back of the cover is provided with an elongated slot 12 terminating in a hole 13. The latching bar 14 is adapted to ride in this slot and when the cover is in its raised position to engage the aperture 13 to hold it in such position. This latching bar 14 is held in said slot by a coil spring 17 mounted in a recess 40 near the base 1, as indicated in Figure 4. The right-hand end of the latching bar, as viewed in Figure 4, is in screw threaded engagement with the screw threaded aperture 15 of the yoke 16 which is pivotally connected at 41 to a fastening screw 42, which latter may be driven into the base 1, or otherwise attached to said base.

By reference to Figure 2 it will be noted that the seat, with the cover in closed position, provides a construction wherein the base is completely covered by the several parts forming the back, the armrests, safety bar and upright members.

It will be readily appreciated that the seat is quickly detachable from the conventional toilet seat. It is constructed of a minimum number of parts, the majority of which may be made of wood or moldable material. The entire seat may be used in place of the conventional toilet seat.

Having fully described my invention and a preferred embodiment thereof, it is to be understood that the invention is not limited by the specific illustration given but by the full scope of the appended claims.

I claim:

1. In a detachable toilet seat, a base, said base having a front portion and a rear portion, said front portion including an aperture, said rear portion including raised side portions and a raised rear portion, and a back, means pivoting said back to said rear portion, said back when in closed position lying in juxtaposed position to said raised side portions and rear portions, a pair of armrests, means pivoting said armrests to said back, a pair of upright members, and means pivoting each upright member to an armrest and to

a raised side portion, said back, arm rests, raised side portions and upright members all having surfaces which lie in substantially the same plane when said back, arm rests, and upright members are in their folded position.

2. In a detachable toilet seat, a base, said base having a front portion and a rear portion, said front portion including an aperture, said rear portion including raised side portions and a raised rear portion, and a back, means pivoting said back to said rear portion, said back when in closed position lying in juxtaposed position to said raised side portions and rear portion, and means for retaining said back in a raised or a lowered position including a latching bar, means pivotally mounting said latching bar on said rear portion of said base, a spring having one of its ends attached to said rear portion and its other end attached to said latching bar, said top having an aperture whereby said latching bar may hold said back in raised position when said latching bar engages said aperture, and may hold said back in lowered position when said latching bar is out of engagement with said aperture.

3. In a detachable toilet seat, a base, said base having a front portion and a rear portion, said front portion including an aperture, said rear portion including raised side portions and a raised rear portion, and a back, means pivoting said back to said rear portion, said back when in closed position lying in juxtaposed position to said raised side portions and rear portion, and means for retaining said back in a raised or a lowered position including a latching bar, means pivotally mounting said latching bar on said rear portion of said base, a spring having one of its ends attached to said rear portion and its other end attached to said latching bar, said top having an aperture and a slot terminating in said aperture whereby said latching bar may hold said back in raised position when said latching bar engages said slot.

4. In a detachable toilet seat, a base, said base having a front portion and a rear portion, said front portion including an aperture, said rear portion including raised side portions and a raised rear portion, and a back, means pivoting said back to said rear portion, said back when in closed position lying in juxtaposed position to said

raised side portions and rear portion, and means for retaining said back in a raised or a lowered position including a latching bar, means pivotally mounting said latching bar on said rear portion of said base, a spring having one of its ends attached to said rear portion and its other end attached to said latching bar, said top having an aperture and a slot terminating in said aperture whereby said latching bar may hold said back in raised position when said latching bar engages in said slot, and a recess in said rear portion, and means mounting said spring and said latching bar mounting means in said recess.

5. In a detachable toilet seat, a base, said base having a front portion and a rear portion, said front portion including an aperture, said rear portion including raised side portions and a raised rear portion, and a back, means pivoting said back to said rear portion, said back when in closed position lying in juxtaposed position to said raised side portions and rear portions, a pair of arm rests, means pivoting said arm rests to said back, a pair of upright members, means pivoting each upright member to an arm rest and to a raised side portion, said back, arm rests, raised side portions and upright members all having surfaces which lie in substantially the same plane when said back, arm rests, and upright members are in their folded position, the front portion of said base being curved, and a safety bar pivotally mounted on said arm rests, said safety bar having a curvature substantially the same as said front curved portion.
